UNITED STATES PATENT OFFICE.

CHARLES L. PLUNKETT, OF BROOKLYN, NEW YORK, ASSIGNOR TO AMERICAN COUCH COMPANY, OF BROOKLYN, NEW YORK, A CORPORATION OF NEW YORK.

COUCH-BED.

1,148,797.

Specification of Letters Patent. Patented Aug. 3, 1915.

Application filed April 1, 1911. Serial No. 618,268.

To all whom it may concern:

Be it known that I, CHARLES L. PLUNKETT, a citizen of the United States, residing at Brooklyn, in the county of Kings and State of New York, have invented certain new and useful Improvements in Couch-Beds, of which the following is a specification.

This invention relates to improvements in couch beds, and more particularly to that class of couch beds known as shiftable or sliding couch beds made up of a pair of sections, one usually designated as the main or stationary section and the other as the shiftable or sliding section, which latter is shiftable relatively to the main or stationary section to form a single couch or to form a double bed, the object of the invention being to provide an improved structure of this character which can be more readily shipped than has heretofore been possible in couches of this kind, while at the same time retaining all of the advantageous features, including simplicity and rigidity of structure, inexpensiveness to manufacture and durability, heretofore present in this form of couch bed.

Heretofore these couch beds have been made with fixed or rigid legs or supports, this being made necessary by reason of the fact that to prevent the collapsing of the end frames thereof under the tension of the yielding mattress support or metallic fabric and the weight of the user suitable side bars secured to the legs had to be provided, and in order to prevent the end frames from spreading suitable tie or tension rods secured to the legs below the side bars had also to be provided in a manner similar to that shown in the Luppino Patent No. 898,981, in which the side bars are designated as 10 and the tension rods or strips as 12. By reason of the location of these tension rods it was therefore impracticable to construct the bed sections so that the legs could fold, in consequence of which the couch bed had to be shipped as double first-class freight. No way was perceived heretofore of avoiding this difficulty while at

the same time using, as was necessary, the tension strips or rods.

In the present improvement, however, while the tension strip or rod is retained it is so located that one portion or half of each leg or support may be folded, in consequence of which it is now possible to ship the structure as second class freight, thus considerably reducing the expense of shipment, which is a very material factor in the manufacture of this class of goods.

In the drawings accompanying and forming part of this specification, Figure 1 is a perspective view of this improved couch bed with the sections assembled to form a double bed; Fig. 2 is a perspective view of one of the sections detached from its companion section and illustrating it as an independent couch bed; Fig. 3 is an enlarged detail view, partly in section, of one portion of one of the sections; and Fig. 4 is a detail view of a modified form of bracing the leg relatively to the main frame.

Similar characters of reference indicate corresponding parts throughout the drawings.

In the preferred form thereof herein shown and described this improved couch bed comprises a pair of bed sections, one usually designated as the main or stationary section, as 2, and the other as the shiftable, movable or sliding section, as 3. In the present instance the sliding section is assembled with the main section in such manner that the yielding mattress supporting means, shown in the form of a stretched metallic fabric 4, slides between a side bar 5 and the metallic fabric 6 of the main section, although this arrangement could be reversed if desired. As each of the sections forming the bed is formed in substantially the same manner, although the sliding section could be provided with two legs only, provided some suitable support is used for supporting the inner side thereof on the main section, a description of one of these sections will be sufficient for the present purposes. Each section, therefore, com-

prises in the present instance a pair of end frames 7 and 8, shown in the present instance as made of angle iron, each end frame being bent to form a pair of legs 9 and 10 and each of the legs being formed as a two-part leg, the lower part being pivotally connected, as at 11, to the upper part thereof, whereby each leg may be folded inwardly and upwardly in the direction of the length 10 of the section. Each of these end frames carries or supports a suitable yielding mattress support, shown in the present instance as a metallic fabric such as 4 or 6 stretched between the end frames and connected thereto in the usual manner. Connecting the upper portions or halves of the legs at each side of the section is a side bar 12, shown as of angle iron formation, which side bar is suitably braced from the end frames by diagonal braces 13. Each pivoted portion 20 of a leg is connected in the form shown in Figs. 1, 2 and 3 by toggle links 14 with the side bars, whereby when the legs are in their upright position the links will be in a dead center position so that the possibility of the legs buckling or folding when the toggle links are in such dead center position is prevented.

The side bars, as hereinbefore stated, prevent the metallic fabric from drawing the end frames toward each other, this metallic fabric being stretched under a good many hundreds of pounds tension, the pull on which end frames is also materially increased 30 by the weight of the user. These side bars, however, are not in themselves sufficient, as has been found in practice, to prevent the end frames from spreading apart and causing the bars when made of angle iron to buckle, and therefore it is necessary to use tension rods or strips to accomplish this. But, as will be immediately apparent, it is not possible to connect the tension strips as heretofore to the hinged portions of the 40 legs or supports, and this has been a serious drawback in the making of structures of this kind as no way heretofore has been perceived of overcoming this serious difficulty. The tension rods or strips 15 in the present 50 instance are shown as in the form of a truss, each being riveted at its ends to the side bars adjacent to the diagonal braces 13 and supported substantially midway thereof by a depending truss member or bar 16 riveted to the tension strip and to the side bar, and which truss prevents the buckling of the side bars and so prevents the spreading of the end frames.

In the form shown in Fig. 4 the legs are 60 formed in the same manner as shown in Figs. 1, 2 and 3, but instead of using toggle links a curved brace 20 is provided, pivotally connected to the hinged portion of the leg and having at its upper end a notch 21

adapted to catch over a pin or projection 65 22 carried by the side bar. By releasing this brace the pivoted portion of the leg may be folded in a similar manner to the structure shown in Figs. 1, 2 and 3.

By means of the present improvement, on 70 shifting the toggle links or the curved brace shown in Fig. 4 the pivoted portions of the legs may be swung upward so that the couch bed will take up very much less room in a freight car than it would require when 75 made as heretofore. And not only this, but the user of the structure may store it away in a much less space than has heretofore been possible.

The present improvement in no way interferes with the separation of the bed sections whereby the same may be used as separate beds in the same or different rooms as occasion may require, or the separation of the bed sections for the purpose of enabling 85 them to be shipped separately if for any reason this should be desired, although in practice the couch bed is shipped as an assembled structure.

I claim as my invention:

1. In an angle iron formed couch bed, the combination of a pair of angle iron end frames each including a pair of depending rigid leg portions and a pair of foldable leg portions foldable inwardly lengthwise of the 95 structure, a spring fabric stretched between each pair of end frames, side-bars connected to the rigid depending leg portions above the folding end portions, tensioning means for the end frames and comprising a truss-formed strip shorter than and connected to each side-bar whereby the ends of said truss-formed strip are spaced inwardly from the end frames, and shiftable bracing means also spaced inwardly at its upper end from 100 each end frame and connected to each side-bar adjacent to the outer spaced end of each truss-formed strip and also connected to a folding leg portion for maintaining the legs in perpendicular position and manually 110 shiftable to permit the legs to be folded.

2. In an angle iron formed couch bed, the combination of a pair of sections one sliding relatively to the other and each comprising a pair of angle iron end frames each 115 including a pair of rigid depending leg portions and a pair of foldable leg portions foldable inwardly lengthwise of the structure, a spring fabric stretched between each pair of end frames, side-bars connected to 120 the rigid depending leg portions above the folding leg portions, tensioning means for each pair of end frames and comprising a truss-formed strip shorter than and connected to each side-bar whereby the ends of 125 said truss-formed strip are spaced inwardly from the end frames, a brace member connected to each end frame and extending in

wardly and connected with each side-bar adjacent to each end of the truss-formed strip, and shiftable bracing means also spaced inwardly at its upper end from each 5 end frame and connected to each side-bar adjacent to the outer spaced end of each truss-formed strip and also connected to a folding leg portion for maintaining the

legs in perpendicular position and manually shiftable to permit the legs to be folded. 10

Signed at 1821 Park Row Building, New York, N. Y., this 29th day of March, 1911.

CHARLES L. PLUNKETT.
